UNITED STATES PATENT OFFICE

HANS ENARD, OF PITTSBURGH, PENNSYLVANIA, ASSIGNOR TO HEYL & PATTERSON, INCORPORATED, OF PITTSBURGH, PENNSYLVANIA, A CORPORATION OF PENNSYLVANIA

HOISTING APPARATUS

Application filed September 25, 1923. Serial No. 664,706.

The present invention relates broadly to hoisting and conveying apparatus, and more particularly to hoisting apparatus of the type employing a grab bucket carried by a trolley or other traversed support, such as is commonly used on coal or ore docks and in storage yards. In apparatus of this character it is customary to mount the bucket hoisting and trolley traversing engines on the trolley which carries the bucket, the operator being located in a cab suspended from one end of the trolley. The grab buckets used with high capacity bridges and unloading towers are usually of the two-rope type having one or two ropes for closing the bucket and another rope or pair of ropes for holding the bucket open.

The most desirable arrangement of the drums for these ropes has been found to be that where the drum for the closing ropes is on the center portion of the drum shaft, with two hold rope drums, one upon each end of the same shaft which carries the closing drum. This gives the maximum spread between the hold ropes and hence offers the greatest resistance to twisting of the bucket when it is being lowered open, and at the same time requires less space for the hoist engine and parts operated thereby than where the drums are mounted on two separate shafts.

The customary method of driving these drums from the hoist motor or motors has been to gear the closing drum permanently to the motor or motors by attaching the drum to the main hoist gear on the drum shaft, both being free to rotate on the shaft, and to provide a clutch between the gear and one of the hold drums, both of the hold drums being keyed to the shaft.

As the clutch on the modern large hoisting apparatus of this type is too large for convenient operation by hand, it has been customary to operate it by means of an air cylinder, which has usually been mounted in one of the hold drums with an air inlet in the end of the drum shaft, the clutch, of the expanding or of the contracting band type, engaging a surface on the hoist gear or sometimes on the closing drum.

An air operated brake band, engaging a suitable surface on one of the hold drums, provides means for holding the bucket suspended after hoisting and while dumping; also, if desired, for assisting in stopping the bucket after lowering. The control of speed when lowering is usually accomplished by dynamic braking on the hoist motor, where direct current is used, and sometimes where alternating current is used. In some cases with alternating current, lowering is done by simply reversing the motor, in which case the bucket drives the motor slightly above synchronous speed so that it acts as a generator and holds the bucket to a uniform speed.

While the above described arrangement provides a construction which is compact, accessible and lighter in weight than other types of construction, an inherent defect incident thereto is the necessity of having the motor rotate while the bucket is opening, due to the direct gear connection between the motor and the closing drum. As the pull of the closing ropes is not enough to accelerate the armature of the hoist motor as rapidly as necessary to avoid loss of time in opening the bucket, it is necessary to supply power to the motor when starting to open the bucket. Even with the expenditure of a relatively large amount of power for accelerating the motor, the opening of the bucket requires several seconds more time with this engine than is needed when the closing drum can be allowed to spin freely by releasing a clutch connecting it to the hoist gear. The amount of electric power taken by the motor while the bucket is opening is an appreciable fraction of the total power consumed in an entire cycle of operations, and hence affects the cost of power for handling the material.

With the type of clutch generally used in constructions of this character, it has not heretofore been found practicable to employ a second air operated clutch on the drum shaft, to permit the closing drum to spin freely when dumping the bucket, on account of the difficulty in getting the supply of air to a cylinder on a drum loosely mounted on the shaft. The space required for sliding

collars on the shaft has prevented the use of that method of operating a clutch for the closing drum on the larger constructions, particularly where the three drums on a single shaft are used. As it is desirable to keep the load suspended from the trolley approximately balanced sideways, the closing drum can not be placed at one end of the drum shaft and the hold drum at the other end, except by reeving the ropes through the bucket and anchoring them on the trolley so that the bucket hangs in a bight of the lines, which requires the ropes to run through the bucket while it is being hoisted and lowered, resulting in a loss of power due to the friction on all the sheaves over which the closing rope passes in the bucket.

By the present invention there is provided a construction which embodies all of the above mentioned advantages incident to having the closing and the two hold drums mounted upon the same shaft, with the hold drums on the ends of the shaft, but in which the objectionable feature of having the closing drum permanently geared to the hoist motor is avoided by the provision of a second clutch to connect the closing drum to the motor, permitting free spinning of the drum for opening the bucket, both clutches being operated by means which does not involve the provision of an air cylinder in any of the drums, thereby obviating the necessity for rotating air connections to take the air into the drum shaft, nor are any sliding collars or similar connections required on the drum shaft.

In the accompanying drawings, there is shown, for purposes of illustration only, one embodiment of the present invention, it being understood that the drawings do not define the limits of the invention, as changes may be made in the construction and operation therein disclosed without departing from the spirit of the invention or the scope of my broader claims.

In the drawings:

Figure 1 is a plan view of the trolley, of a hoisting and conveying bridge structure embodying my invention.

Figure 2 is a side elevation of the trolley and grab bucket suspended therefrom.

Figure 3 is an end view of the main hoisting gear, showing one of the clutches associated therewith and the means for operating the same.

Figure 4 is a sectional view on the line IV—IV of Figure 3.

Figure 5 is a view, partly in elevation and partly in section, of the double acting clutch operating cylinder and parts associated therewith.

Figure 6 is a sectional view taken approximately on the line VI—VI of Figure 5.

Figure 7 is a vertical sectional view taken on the line VII—VII of Figure 5.

Figure 8 is a horizontal sectional view taken on the line VIII—VIII of Figure 3, illustrating a portion of the clutch operating means.

Figure 9 is a sectional view illustrating a solenoid actuated valve for controlling the fluid supply to one end of the double acting cylinder.

Figure 10 is a view illustrating the brake means for one of the hold drums and the fluid pressure actuated means for releasing said brake means; and

Figures 11 and 12 are detail plan views similar to Figure 8.

Referring to Figure 1, the trolley frame 3 carries the usual track engaging wheels 6 mounted upon axles 7 driven by trolley traversing motors 8.

Mounted upon a shaft 9 journaled in the frame 3 are the two hold drums 10 and 11 and the closing drum 12, the hold drums being keyed to the shaft and the closing drum being mounted loosely thereon. Also mounted to rotate freely upon the shaft 9 is a main hoist gear 13, said gear being arranged intermediate the adjacent ends of the hold drum 10 and closing drum 12.

A ring gear 14 (Figure 4) is rotatably supported at one side of the main gear 13 upon rollers 15 mounted upon pins 16 carried by said main gear.

The main gear and ring gear are driven at the same speed by a hoist motor 17. This motor has a pinion 18 mounted upon its armature shaft which meshes with a gear 19 on the end of an intermediate shaft 20 journaled in suitable bearings in the trolley carriage. The intermediate shaft carries a pinion 21 meshing with the main gear 13 and also carries a pinion 22 of the same pitch diameter as the pinion 21. By reference to Figure 7, it will be seen that the pinion 22 meshes with a pinion 23 mounted upon a short shaft 24, the pinion 23 meshing with a pinion 25 journaled upon a shaft 26 beneath and parallel to the shaft 20. Another pinion 27 of the same diameter as the pinion 25 is also rotatably mounted upon the shaft 26 and is integrally connected with the pinion 25 by means of a sleeve 28. The pinion 27 meshes with the ring gear 14. While I have shown the pinions 21 and 22 as being mounted upon an intermediate shaft 20, it will be apparent that these pinions might be mounted directly upon the armature shaft, if desired, and the pinion 18 and gear 19 eliminated.

Referring to Figures 5 and 6, the pinion 23 is adapted to be moved a short distance in opposite directions from its central position, in which its axis is in the same vertical plane as the axes of the pinions 22 and 25. For this purpose the pinion 23 is operatively connected to a double acting fluid pressure cylinder 29, the piston 30 whereof has its piston

rod 31 pivotally connected to one end of a pair of bars 32 arranged at opposite sides of the pinion and having the short shaft 24 extending therethrough. These bars extend through a guide 33. Each end of the shaft 24 extends through an eye 34 formed on the end of a stem 36. Each stem 36 extends through two spaced plates 37 and 38, which are slidably mounted upon a pair of parallel rods 39 projecting from an end wall of the cylinder 29. Each stem 36 is surrounded by a coil spring 40 which abuts at its ends against the plates 37 and 38 and normally maintains these plates in engagement with nuts 41 and 42 on the rods 39. These springs normally maintain the pinion 23 in its central position, in which position of the pinion both ends of the cylinder 29 are open to the exhaust.

The opposite ends of the cylinder 29 are connected by pipes 43 and 44 with valve casings 45 and 46. These valve casings are connected by other pipes 47 and 48 to a pipe 49 leading to a suitable source of pressure fluid supply, preferably compressed air. The valves in these valve casings may be operated by any suitable means and I show, for purposes of illustration only, solenoids 50 and 51 for that purpose.

The solenoid 50 is shown in detail in Figure 9, it being understood that the solenoid 51 is of identical construction. It comprises a coil 52 surrounding a stationary hollow core 53. A plunger 54 is mounted in said core and carries an armature 55 upon its upper end. The lower end of the plunger constitutes a valve 56 adapted to engage a valve seat in the upper end of a sleeve 57. The valve 56 is connected by a valve stem 58 with another valve 59 adapted to engage a valve seat in the lower end of the sleeve 57. The valve casing 45 has a chamber 60 therein beneath the sleeve 57 and communicating with this chamber is the supply pipe 47 leading from the source of fluid supply. The pipe 43 leading to one end of the cylinder 29 is tapped into the valve casing and communicates with the interior of the sleeve 57. The valve casing has another chamber 61 therein above the sleeve 57 and this chamber communicates with an exhaust port 62. A spring 63 in the chamber 60 engages the valve 59 to normally maintain it against its seat and the valve 56 away from its seat. Under these conditions the end of the cylinder which is connected by the pipe 43 with the valve casing is open to the exhaust. When, however, the coil 52 is energized, the armature 55 is attracted towards the core 53, thereby moving the valve 56 into engagement with its seat and the valve 59 away from its seat. This cuts off the end of the cylinder from the exhaust and places it in communication with the source of fluid supply through the pipe 43, sleeve 57, chamber 60 and pipe 47.

The operation of the parts shown in Figure

5 and 6 is as follows: Normally, as already stated, both ends of the cylinder 29 are open to the exhaust and the springs 40 maintain the pinion 23 in its central position. Let it be assumed that the solenoid 50 is energized. This places the right-hand end of the cylinder 29 as viewed in Figures 5 and 6 in communication with the source of fluid supply, the left-hand end of the cylinder remaining open to the exhaust. The piston 30 is therefore moved to the left, thereby moving the shaft 24 in the same direction. The pinions 25 and 27 will, therefore, be rotated in a counter-clockwise direction through an angle corresponding to twice the amount of motion of the shaft 24, since the tooth contact between the pinions 22 and 23 serves as the fulcrum of a lever of the third class. The ring gear 14 will, therefore, be rotated in a clockwise direction, as viewed in Figure 3 relative to the main gear 13. It will be apparent that the distance moved by the teeth of the ring gear will be equal to twice the distance moved by the shaft 24. It will also be apparent that this relative movement between the ring gear 14 and main gear 13 will take place irrespective of whether the pinion 22 is being driven by the hoist motor 17 or is stationary. If instead of the solenoid 50 being energized the solenoid 51 is energized, then the piston 30 will be moved to the right and consequently the pinions 25 and 27 will be rotated in a clockwise direction and the ring gear 14 will be rotated in a counter-clockwise direction relative to the main gear 13.

The springs 40 will be put under compression upon movement of the piston 30 in either direction. When the piston moves to the left the eyes 34 on the stems 36 engage the plates 37 and move them to the left, thereby compressing springs 40, and when the piston moves to the right the nuts on the ends of the stems 36 engage the plates 38 and move them to the right, thereby compressing the said springs.

Referring to Figure 4, the drums 10 and 12 have flanges 63 and 64 on their adjacent ends positioned within the rim of the main gear. The peripheral surfaces of these flanges constitute clutch engaging surfaces. The main gear has associated therewith a clutch for cooperation with the clutch surface of the flange 63 of the hold drum 10 and another clutch of identical construction for cooperation with the clutch engaging surface of the flange 64 of the closing drum 12. Therefore, it will only be necessary for the purpose of understanding the present invention to describe one of these clutches.

The clutch for cooperation with the flange 63 of the hold drum 10 is shown in Figure 3. This clutch comprises a clutch band 65 which is anchored at one end upon a pin 66 carried by the main gear. The other end of

this band is pivotally connected to a lever 67 pivotally mounted upon said pin. A connecting rod 68 is pivotally connected at one end to the lever 67 and at its other end is pivotally connected to a lever 69 pivoted upon a pin 70 carried by the main gear. A stem 71 is pivotally connected at one end to said lever 69 and extends through an opening in a spoke of the main gear. Said stem has a nut mounted upon its other end and surrounding the same between said nut and said spoke is a coil spring 72. The spring 72 normally maintains the clutch band in holding engagement with the surface of the flange 63. 15 It will be understood that in like manner a clutch of identical construction is associated with flange 64 and is normally held in holding engagement with said flange.

Relative movement of the ring gear 14 20 with respect to the main gear 13, as effected by the means disclosed in Figures 5 and 6, serves to release one or the other of the clutches as desired. For this purpose the ring gear is operatively connected to the connecting rods 68 and 68' of the respective clutches. This operative connection comprises a T-shaped lever 73 (Figure 8) pivoted upon a pin 74 secured in the main gear 13 and projecting within the interior of the 25 rim thereof. The lever 73 is hollow to receive a pin 75 which is pivoted at one end to the ring gear 14 upon a pin 76 carried by said ring gear. It will be seen that relative movement of the ring gear 14 in one direction or 30 the other with respect to the main gear 13 will rock the lever 73 about its pivot 74. The lever 73 is connected by links 77 with a lever 78 pivoted upon a pin 79 carried by the main gear. By reference to Figure 11 it will be 35 seen that the opposite ends of the lever 78 extend into horizontal slots in the connecting rods 68 and 68' and carry pins 80 and 81 which extend through vertical longitudinal 40 arcuate slots 82 and 83 intersecting said horizontal slots. These pins are normally both positioned adjacent corresponding ends of 45 said slots 82 and 83. As shown, the pins are positioned adjacent the left-hand ends of the slots.

50 The operation of the clutch releasing means is as follows: Normally the clutches maintain the drums 10 and 12 operatively connected to the main gear. If it is desired to release the closing drum 12 from the main gear in order to open the bucket, for example, the solenoid 51 will be energized, thereby causing the piston 30 to be moved to the right and the pinion 27 to be rotated in a clockwise direction. Consequently the ring gear will be rotated in an anti-clockwise direction relative to the main gear, thereby 55 rocking the lever 78 about its pivot 79. This will cause the pin 80 to engage the end wall of the slot 82 and move the connecting rod 68' to the left to release the clutch engaging

the flange 64. Rocking of the lever 78 for this purpose will have no effect whatever upon connecting rod 68 of the clutch engaging flange 63 of hold drum 10, for the reason that the pin 81 will simply travel in the slot 83 but will not travel far enough to engage the opposite end wall of the slot 83 and move connecting rod 68 to the right. On the other hand, if it is desired to release the clutch engaging the flange 63 of hold drum 10 in order to close the bucket, for example, the solenoid 50 will be energized, thereby effecting movement of the piston 30 to the left. This will result in the pinion 27 being rotated in a counter-clockwise direction and the ring gear 14 in a clockwise direction with respect to the main gear. The lever 78 will therefore be rocked about its pivot 79 in a direction to cause the pin 81 to engage the end wall of the slot 83 and move the connecting rod 68 of the clutch associated with the flange 63 to the left, thereby releasing the hold drum 10 from the main gear.

55 The other hold drum 11, as is customary, has a brake associated therewith. In Figure 10 I have shown a brake of the character ordinarily employed, which comprises a brake band 84 engaging a rim 85 on the drum 9. One end of the band is anchored upon a pin 86 and the other end is connected to one 60 end of a bell crank lever 87 by means of a connecting rod 88, the lever 87 being pivoted intermediate its ends upon said pin 86. The other end of lever 87 has the end of a piston rod 89 pivoted thereto, said piston rod being 65 connected to a piston 90 working in a fluid pressure cylinder 91. A spring 92 surrounding the piston rod between an adjustable abutment 93 and the piston 90 normally maintains the brake band in holding engagement with the rim. In order to release the brake band pressure fluid may be admitted 70 into the cylinder above the piston through a pipe 94 which is connected to a valve casing 95. This valve casing is connected by a pipe 96 to the source of pressure fluid supply and has an exhaust pipe 97. The valve construction within the casing 95 may be identical 75 with that within the casings 45 and 46 and may be operated by a solenoid 98 of identical 80 construction with the solenoids 50 and 51.

85 A brake 99 may be associated with the armature shaft of the motor 17 in order to prevent a suddenly applied reverse load on the gears and bearings that results from a sudden application of the brake associated with the hold drum 11. This brake may be of the usual shoe or post type which is equally effective in both directions of rotation of the armature shaft and prevents over-travel 90 when the power is shut off the hoist motor.

95 The advantages of the present invention arising from the provision of a second clutch for connecting the main gear to the closing drum and operated in the manner disclosed 100

should be apparent to those skilled in the art. As already pointed out, the provision of the second clutch does not require an air cylinder in the closing drum. Furthermore, the air cylinder heretofore employed in one of the hold drums is eliminated. Consequently no rotating air connections are needed to take the air into the drum shaft. The bucket is dumped in several seconds less time than is possible when the hoist motor must rotate during the dumping and there is a considerable saving in power consumption and in the wear and tear on the hoist motor and associated parts.

The above are important advantages arising from the invention but there are still others. By the provision of means for operating both clutches comprising a pinion shiftable in one direction to release one of the clutches and shiftable in the opposite direction to release the other of said clutches, it is impossible for the operator to inadvertently release both clutches at the same time. A double acting fluid pressure cylinder of the type shown mounted upon the trolley frame floor is a desirable means for controlling the movements of the shiftable pinion, as the cylinder, being stationary, is accessible for inspection while the hoist is being operated, and repairs are more easily made than where the cylinder is inside of a drum. However, other means may be employed with equally good results for actuating the shiftable pinion, for example two solenoids or two single acting cylinders might be used or a hand lever might be employed for changing the position of the pinion while still retaining the advantage of being unable to hold both clutches released at the same time.

A further advantage arising from the provision of means of the character shown for controlling both clutches is due to the fact that the release of one clutch cannot take place while the other clutch remains released, as, for example, because of any binding or other mechanical trouble preventing the other clutch from going to the clutch-applied position. This fact will be apparent from a consideration of Figure 12. Let it be assumed that the connecting rod 68' has been shifted to the left to release the clutch of the closing drum and that upon return of lever 78 to normal position, as shown in dotted lines, said connecting rod 68' remains in the position shown by reason of binding or other mechanical trouble. In that case the pin 80 is positioned at the right-hand end of slot 82, as shown in dotted lines. If thereafter the ring gear 14 is moved in a direction to shift the connecting rod 68 to the left to release the clutch of the hold drum 10, the pin 80 will engage the right-hand end wall of the slot 82 and positively move the connecting rod 68' to the right to thereby apply the clutch to the closing drum. In case the binding action is

such as to prevent movement of the connecting rod 68' to the right, then the ring gear 14 will simply be held against relative movement with respect to the main gear 13 and the hold drum clutch will not be released. The same thing will take place in case the hold drum is held in the released position and it is attempted to release the closing drum clutch.

I claim:

1. Hoisting apparatus, comprising a drum shaft, a pair of drums on said shaft, a driving means on said shaft, clutches for operatively connecting said driving means to said drums, a common clutch actuating mechanism for both drums rotatable about the axis of the shaft and connected for rotation with the driving means, and means for effecting relative rotation of the clutch actuating mechanism and the driving means for controlling said clutches, substantially as described.

2. Hoisting apparatus, comprising a drum shaft, a pair of drums on said shaft, a driving means on said shaft, clutches for operatively connecting said driving means to said drums, a common clutch actuating mechanism for both drums rotatable about the axis of the shaft and connected for rotation with the driving means, means for effecting operative rotation of the actuating mechanism in one direction for disconnecting one drum from the driving means, and means for effecting operative rotation of said actuating mechanism in the other direction for disconnecting the other drum from the driving means, substantially as described.

3. Hoisting apparatus, comprising a drum shaft, a pair of drums on said shaft, a driving means on said shaft, clutches for operatively connecting said driving means to said drums, a common clutch actuating mechanism for both drums rotatable about the axis of the shaft and connected for rotation with the driving means, means for effecting operative rotation of the actuating mechanism in one direction for disconnecting one drum from the driving means, and means for effecting operative rotation of said actuating mechanism in the other direction for disconnecting the other drum from the driving means, the clutches and clutch actuating mechanism being arranged to disconnect either of the drums from the driving means or to simultaneously connect both drums to the driving means, substantially as described.

4. Hoisting apparatus, comprising a drum shaft, a pair of drums on said shaft, a driving means on said shaft, clutches for operatively connecting said driving means to either of said drums, clutch actuating mechanism, a portion of which is common to both drums and is rotatable about the axis of the shaft, gearing for rotating the clutch actuating mechanism in synchronism with the driving means and means for shifting said gear-

ing about the axis of the driving means and independent thereof for controlling said clutches, substantially as described.

5. Hoisting apparatus, comprising a drum shaft, a pair of drums on said shaft, a driving means on said shaft, clutching means for operatively connecting the driving means to either of said drums, a common means mounted in part upon said driving means and 10 rotatable therewith, for controlling both clutches, and means for shifting said last mentioned means about the axis thereof relative to the driving means substantially as described.

15. 6. Hoisting apparatus, comprising a drum shaft, a pair of drums on said shaft, a driving means on said shaft, clutches for operatively connecting said driving means to either of said drums, clutch actuating mechanism 20 rotatable about the axis of the shaft, gearing for rotating the clutch actuating mechanism in synchronism with the driving shaft, and fluid actuated means for shifting said gearing to effect a relative rotation of the clutch 25 actuating mechanism and the driving means for controlling said clutches, substantially as described.

7. Hoisting apparatus, comprising a drum shaft, a pair of drums on said shaft, a driving 30 means on said shaft, clutches for operatively connecting said driving means to either of said drums, clutch actuating mechanism rotatable about the axis of the shaft, gearing for rotating the clutch actuating mechanism 35 in synchronism with the driving shaft, and double acting fluid pressure means for shifting said gearing to effect a relative rotation of the clutch actuating mechanism in two directions with relation to the driving 40 means for controlling said clutches, substantially as described.

8. Hoisting apparatus, comprising a drum shaft, a pair of drums on said shaft, a driving means on said shaft, clutches for operatively 45 connecting said driving means to either of said drums, clutch actuating mechanism rotatable about the axis of the shaft, gearing for rotating the clutch actuating mechanism in synchronism with the driving shaft, and double acting fluid pressure means for shifting 50 said gearing to effect a relative rotation of the clutch actuating mechanism in two directions with relation to the driving means for controlling said clutches, the clutches and 55 gearing being arranged to disconnect either of the drums from the driving means or to simultaneously connect both drums to the driving means, substantially as described.

9. Hoisting mechanism having a drum, 60 driving means for the drum, clutch elements connected to the driving means and the drum, one of said elements comprising an expandable and contractible member, actuating means rotatable relative to the driving means 65 and about the axis of the drum for expand-

ing and contracting said member, a second driving means for rotating the actuating means in synchronism with the first mentioned driving means, and means for supplementally actuating said second driving means relative to the first mentioned driving means for expanding and contracting said member, substantially as described. 70

10. Hoisting mechanism comprising a plurality of drums, driving means for the drums, 75 clutches for connecting the drums to the driving means, each clutch member comprising an expandable band carried by the driving means, actuating means rotatable relative to the driving means for expanding and contracting the band, a second driving means for rotating the actuating means in synchronism with the first mentioned driving means, and means for shifting said second driving means in two directions relative to the first mentioned driving means for contracting and expanding the band, substantially as described. 80

11. Hoisting mechanism having a drum, 85 driving means for the drum, clutch elements connected to the driving means and the drum, one of said elements comprising an expandable and contractible member, actuating means rotatable relative to the driving means and about the axis of the drum for expanding and contracting said member, a second driving means for rotating the actuating means in synchronism with the driving means, and fluid pressure means for supplementally actuating said second driving means 90 relative to the first mentioned driving means for expanding and contracting said member, substantially as described. 95

12. Hoisting mechanism comprising a plurality of drums, driving means for the drums, 100 clutches for connecting the drums to the driving means, each clutch member comprising an expandable band carried by the driving means, actuating means rotatable about the driving means for expanding and contracting the band, second driving means for rotating the actuating means in synchronism with the first mentioned driving means, and fluid pressure means for supplementally actuating said second driving means 105 in two directions relative to the first mentioned driving means for contracting and expanding the band, substantially as described. 110

13. Hoisting apparatus, comprising a drum shaft, a pair of drums on said shaft, a main gear on said shaft, means for driving said gear, a clutch for operatively connecting said gear to one of said drums, a clutch for operatively connecting said gear to the other of said drums, and means common to both 115 clutches for normally operating them independently, said means comprising a train of gears one of which is rotatably mounted on said main gear and operatively connected to said clutches and another of which is bodily 120

125

shiftable in one direction to effect operation of one of said clutches and bodily shiftable in the opposite direction to effect operation of the other of said clutches through said rotatable gear, substantially as described.

5 14. Hoisting apparatus, comprising a drum shaft, a pair of drums on said shaft, a main gear on said shaft, means for driving said gear, a clutch for operatively connecting said gear to one of said drums, a clutch for operatively connecting said gear to the other of said drums, and means common to both clutches for normally operating them independently, said means comprising a train of 10 gears one of which is rotatably mounted on said main gear and operatively connected to said clutches and another of which is bodily shiftable in one direction to effect operation of one of said clutches and bodily shiftable 15 in the opposite direction to effect operation of the other of said clutches through said rotatable gear, the arrangement being such that either or both clutches can be maintained in clutching engagement with their drums.

20 15. Hoisting mechanism having a drum, driving means for the drum, clutch elements connected to the driving means and the drum, one of said elements comprising an expandable and contractible member, actuating 25 means rotatable about the axis of the driving means for expanding and contracting said member, driving mechanism for rotating the actuating means in synchronism with the driving means, said driving mechanism 30 including a gear having a shiftable spindle, and means for shifting said spindle for shifting said driving mechanism about the axis of the driving means and relative to the driving means for expanding and contracting said 35 member, substantially as described.

40 16. Hoisting apparatus, comprising a pair of drums, a main gear, means for driving said gear, a clutch normally operatively connecting said gear to one of said drums a clutch 45 normally operatively connecting said gear to the other of said drums, each of said clutches comprising a spring-applied band engageable with a surface of the corresponding drum, and means for actuating said clutches independently to released position, said means being effective to positively return one clutch to clutch-applied position simultaneously with the actuation of the other clutch to released position, substantially as described.

55 17. Hoisting apparatus, comprising a drum shaft, a pair of drums on said shaft, a main gear on said shaft, a clutch for operatively connecting said gear to one of said drums, a clutch for operatively connecting said gear 60 to the other of said drums, a ring gear rotatably mounted upon said main gear and operatively connected to both of said clutches, and means including a gear train for normally driving said main and ring gears at the same 65 angular speed, one gear of said train being

bodily movable in one direction to effect a relative rotation in one direction between said main and ring gears to operate one of said clutches and bodily movable in the opposite direction to effect a relative movement between said main and ring gears in the opposite direction to operate the other of said clutches, substantially as described.

70 18. Hoisting apparatus, comprising a pair of drums, driving means, a spring-applied band clutch for connecting said driving means with one of said drums, a spring-applied band clutch for connecting said driving means with the other of said drums, and controlling means for said clutches including means for positively returning either of them from released to applied position simultaneously with the movement of the other thereof to released position, substantially as described.

75 19. Hoisting apparatus, comprising a pair of drums, driving means, a spring-applied band clutch for connecting said driving means with one of said drums, a spring-applied band clutch for connecting said driving means with the other of said drums, and means common to said clutches for moving either of them to released position independently of the other and including means for positively returning either of said clutches from released to applied position simultaneously with the movement of the other to released position, substantially as described.

80 20. Hoisting apparatus, comprising a pair of drums, driving means, a friction clutch for connecting said driving means with one of said drums, a friction clutch for connecting said driving means with the other of said drums, each of said clutches including spring means for normally maintaining it applied, and means common to said clutches for moving either of them to released position independently of the other and including means for positively returning either of said clutches from released to applied position simultaneously with the movement of the other to released position, substantially as described.

85 21. Hoisting apparatus, comprising a pair of drums, driving means, a spring-applied band clutch for operatively connecting said driving means with one of said drums, a spring-applied band clutch for operatively connecting said driving means with the other of said drums, and means for releasing said clutches independently, said means being incapable of releasing both of said clutches at the same time, substantially as described.

90 22. Hoisting mechanism having a plurality of drums, driving means for the drums, a clutching element connected to each drum, a clutch band for each clutching element connected to the driving means, actuating means rotatable about the axis of the driving means for contracting and expanding the clutch bands, gearing for rotating the actuating

means in synchronism with the driving means, said gearing including a gear having a shiftable spindle, and means for shifting said spindle a predetermined distance in opposite directions for shifting said driving mechanism about the axis of the driving means and relative to the driving means for expanding and contracting either of said bands, substantially as described.

10 23. Hoisting apparatus, comprising a pair of drums, driving means, a spring-applied band clutch for operatively connecting said driving means with one of said drums, a spring-applied band clutch for operatively connecting said driving means with the other of said drums, and means for releasing said clutches independently, said means operating to positively insure either of said clutches being maintained in applied position when the other is in released position, substantially as described.

24. Hoisting apparatus, comprising a drum, driving means therefor, clutch means rotatable with the driving means and effective for controlling the operative connection of the driving means with the drum upon non-synchronous rotation of the driving means and the clutch means, a second driving means for rotating the clutch means in synchronism with the first mentioned driving means, and means for effecting non-synchronous rotation of the driving means.

25. Hoisting apparatus comprising a drum shaft, a pair of drums on said shaft, a driving means on said shaft, clutches for operatively connecting said driving means to either of said drums, a common actuating means for actuating the clutch of either drum and rotatable with a drum after its clutch has been actuated, and means for rotating said actuating mechanism relative to the drums so as to control said clutches, substantially as described.

In testimony whereof I have hereunto set my hand.

HANS ENARD.
